US0D1000150S

(12) **United States Design Patent** (10) Patent No.: **US D1,000,150 S**
(45) Date of Patent: ** Oct. 3, 2023

(54) **DISPLAY STAND**

(71) Applicant: **Guangzhou Xiwang Technology Co., Ltd.**, Guangzhou (CN)

(72) Inventor: **Qiaotong Wei**, Yunfu (CN)

(**) Term: **15 Years**

(21) Appl. No.: **35/515,196**

(22) Filed: **Jul. 27, 2022**

(80) **Hague Agreement Data**

Int. Filing Date: **Jul. 27, 2022**

Int. Reg. No.: **DM/223373**

Int. Reg. Date: **Jul. 27, 2022**

Int. Reg. Pub. Date: **Sep. 23, 2022**

(51) **LOC (14) Cl.** **06-06**

(52) **U.S. Cl.**

USPC **D6/407**; D6/672; D20/40; D19/90; D19/91
